UNITED STATES PATENT OFFICE.

JAMES A. STRANGE, OF ELLENSBURG, WASHINGTON.

SHOEMAKER'S JACK.

1,405,875.

Specification of Letters Patent. Patented Feb. 7, 1922.

Application filed July 6, 1920, Serial No. 394,329. Renewed December 19, 1921. Serial No. 523,584.

To all whom it may concern:

Be it known that I, JAMES A. STRANGE, a citizen of the United States, residing at Ellensburg, in the county of Kittitas and 5 State of Washington, have invented a certain new and useful Improvement in Shoemaker's Jacks, of which the following is a specification.

My invention relates to improvements in 10 shoemakers' jacks and the object of my invention is to provide a jack comprising a vertically adjustable telescopic standard, the male member of which is rotatably mounted within the female member thereof 15 and adapted to be releasably engaged therein in any desired position.

Another object is to provide a telescopic and rotatable shoemaker's jack embodying a removable arm adapted to be disposed on 20 the tongue or upper end of the said jack, the said arm comprising a relatively fixed socket member and a relatively movable member which is mounted for rotation on its own axis in the said socket member and 25 which is further adapted to be clamped in any desired position in the said socket member.

A further object is to provide a shoemakers' jack that embodies simplicity, 30 economy and durability in construction, that is positive and efficient in operation and that will not readily get out of order.

With the above and other objects in view the invention consists of the novel construction, adaptation and combination of 35 parts as will be hereinafter described and claimed.

I accomplish these objects by devices 40 illustrated in the accompanying drawings wherein Fig. 1 is a side elevation, partly in vertical section, of a shoemaker's jack constructed in accordance with this invention.

Fig. 2 is a view in horizontal section, 45 substantially as shown on a broken line 2, 2 of Fig. 1;

Fig. 3 is a view in horizontal section, 50 substantially as shown on a broken line 3, 3 of Fig. 1.

Fig. 4 is a front elevation, partly in vertical section, showing the means by which the upper end of the lifting rod is attached to the standard, and with the removable arm in adjusted position.

Fig. 5 is a plan view with the removable arm in an adjusted position; and

Fig. 6 is a fragmentary view in vertical section, substantially on a broken line 6, 6 of Fig. 4, and shows the means by which the removable arm is attached to the 60 standard.

Referring to the drawings throughout which like reference numerals indicate like parts, the numeral 5 designates a base into which the female member 6 of a telescopic 65 adjustable standard is threaded. The numeral 7 designates the male member of said standard. Spaced at convenient intervals, transverse holes 8 are provided in the female member into which fits a pin 9, said 70 pin carrying the weight of said male member by fitting into slots 10 or 11 provided in the lower end of said male member. A foot lever 12 is secured to said female member by a pivot 13, and to a lifting rod 14 by a 75 pin 15. The upper end of said lifting rod is bent to form a loop 16 which fits under a collar 17, said collar being adjustably secured to the male member 7 by means of a set screw 18. Said male member terminates in a tongue 19 to which either a last 20 or a removable arm 21 is mounted by means of a rectangular slot 22. Said removable arm is composed of an offset member 23 and a longitudinal member 24, revolvably 85 mounted therein by a reduced end 25 secured by a set screw 26. The end of a hook 27 passes through said longitudinal member, secured to the hook end of which is a spiral spring 28 to which a cord 29 is fastened. Said cord passes around the last or shoe and is secured to the other end of said hook substantially as shown. The longitudinal member 24 terminates in a tongue 90 30 to which a last is secured in the usual 95 manner.

With the aforesaid objects in view, and with reference to the drawings, it will be seen that instead of the shoemaker having to contort himself into awkward, unnatural 100 and uncomfortable positions while engaged at his trade, with the device herein described, he can readily adjust his work to suit his comfort and convenience. This is accomplished by sliding the stand along the floor 105 to any position desired for convenience of light, heat, ventilation, etc. Then by operating the foot lever and inserting the pin 9 in the hole 8 at the desired height the device is ready for use in working on the soles 110 of foot wearing apparel. It will be seen that by providing two slots at right angles

to each other in the lower end of the male member 7, the workman may readily turn the shoe, upon which he is working, to any one of two different positions by lifting the 5 male member by means of the foot lever and its associated parts until the slot clears the pin and revolving same to the desired position. When sewing or working on the upper part of a shoe the arm 21 replaces the 10 last 20, which is shifted to the tongue 30, and the shoe or other foot wearing apparel is securely held on the last by fastening the cord around same at the desired tensions, and the work is revolved vertically by use 15 of the set screw 26 and horizontally by turning the male member 7 within the female member 6 to the desired angle.

From the above description taken in connection with the accompanying drawing, 20 the advantages of the construction and of the method of operation of my shoemaker's stand will be readily apparent to those skilled in the art to which the invention relates, but, while I have described the principle 25 of operation of the invention together with the device which I now consider to be the best embodiment thereof, I desire to have it understood that the stand shown is merely illustrative and that such changes 30 may be made as are within the scope of the following claims.

I claim:

1. A jack comprising a base, a telescopic standard consisting of male and female members, a pin removably positioned at different heights transversely of the female member, the lower end of the male member having crossed slots for selective seating on 35 said pin, a collar adjustably connected to the male member, a foot lever pivoted to the female member, a link rod connection between the collar and lever for elevating the main member, and a last carried by the other end of the male member.

2. A jack comprising a base, a telescopic 45 standard consisting of male and female members, a pin removably positioned at different heights transversely of the female member, the lower end of the male member having crossed slots for selective seating on 50 said pin, a collar adjustably connected to the male member, a foot lever pivoted to the female member, a link rod connection between the foot lever and male member including a ring carried by the link rod and 55 inclosing the male member beneath the collar, and a last carried by the other end of the male member.

In witness whereof, I hereunto subscribe my name this 25th day of June A. D. 1920. 60

JAMES A. STRANGE.
